FORM FOR CASTING REFLECTING FACE CURB

Emil Behringer, Richmond Hill, N. Y., and Maurice R. Harrison, Maplewood, N. J., assignors to E. Behringer Sheet Metal Works, Inc., Newark, N. J., a corporation of New Jersey.

Application January 17, 1940, Serial No. 314,200

6 Claims. (CL 25—118)

This invention relates to molding and to means for molding concrete or cement curbing and more particularly to apparatus for molding road curbing having transverse light-reflecting faces, though it is noted that in some of the claims the invention is not limited to molding curbing.

Objects of the invention are to provide strong, durable accurate molds having smooth molding faces and sharp edges. Another object is to provide such molds for accurately casting curbing having flutes forming reflecting faces for reflecting light back to an on-coming automobile. This reflecting face curbing is not a part of our invention.

The economical production of sharp, smooth, unwarped molds for the above purpose presented a problem, and it was after considerable investigation and work that we were able to solve the problem. This we did by die-casting the molding form plates and securing these form plates to steel or other strong backing plates. Such die castings may be of zinc or aluminum alloy, synthetic resin or other suitable alloy, metal, plastic or material. The die-cast form plates provide smooth sharp molding faces without the expense of machining.

Other objects of the invention are to provide improved molding units in which one or more suitable form plates forming molds as above described are secured to a strong metal backing plate to form molding units adapted to be secured in end-to-end relation.

Other objects are to provide suitable molding for casting reflecting faces and other curbing for straight and curved roads.

Other objects are to provide improved means for casting the curbing in situ, and for pre-casting curbing for later transportation to the roadway.

Additional objects of the invention are to effect simplicity, efficiency, reliability and economy in such molds.

Other objects will appear as the description proceeds; and while herein details of the invention are described, many and various changes may be made without departing from the scope of invention as in the broader claims.

The herein inventive features are shown in connection with molding units, each of which briefly stated, includes a backing plate of steel or other suitable metal, and one or more die-cast form plates secured against the backing plate. The form plate may be provided on the molding face with light reflecting transverse shoulders or with other suitable molding face.

In one form of the invention, the molding unit is supported, at the edge of the pavement by a protection plate disposed over an expansion joint at said edge, the molding face at the top and bottom margins having wide rabbets to form a base and top molding on the curbing. The upper edge of the unit is adapted to guide a trowel plate movable along the cement to cooperate with the upper rabbet to form the top molding. In this form, key plates are secured to adjacent ends of the backing plates, with which plates a binder member engages for locking the key plates, and consequently the units, together.

In another form of the invention, the backing plate comprises the bottom of a molding trough against which bottom the form plates are secured to provide a mold for precasting the curbing. Other modifications are shown and described.

In the accompanying drawings showing several of many possible embodiments of the invention, Fig. 1 is a fragmental side elevation showing one form of unit;

Fig. 2 shows a section taken on the line 2—2 of Fig. 1;

Fig. 3 is an end elevation of the unit of Fig. 1;

Fig. 4 shows a broken transverse section of curbing which may be molded by our invention, this curbing being not our invention;

Fig. 5 is a fragmental side elevation of this curbing;

Fig. 6 is a side elevation showing an end of a backing plate with a plate attached;

Fig. 7 is an end view showing the backing plate as in Fig. 6;

Fig. 8 is a fragmental side elevation showing end-to-end backing plates with the binder or yoke member about to move into wedging and locking position;

Fig. 9 shows a section taken on the line 9—9 of Fig. 8;

Fig. 10 is a fragmental sectional view taken on the line 10—10 of Fig. 8;

Fig. 11 is a perspective of the yoke or binder member;

Fig. 12 is a fragmental plan showing a modified unit having a long backing plate;

Fig. 13 is a horizontal sectional view, partly in plan, showing a modified form plate;

Fig. 14 is a horizontal sectional view, partly in plan, showing a backing plate longer than the form plate;

Fig. 15 is a fragmental plan showing a unit with long curved backing plate and modified

form plates for molding curbing for curves in a roadway;

Fig. 16 is a fragmental plan showing a curved unit using the form plate of Fig. 13;

Fig. 17 is a fragmental plan showing a curved unit using a backing plate as in Fig. 1;

Fig. 18 is a fragmental transverse vertical sectional view, partly in perspective, showing a molding unit as in Figs. 1 to 3, in use for molding the curbing;

Fig. 19 is a perspective view showing the molding trough for pre-casting the curbing.

The forms of the invention shown in Figs. 1 to 18 are for molding, in situ, cement curbing and are suitable for molding curbing 10 (Figs. 14 and 18) extending below and adjacent to the side face of the road pavement 11 as in Fig. 18. While the invention is adaptable for various kinds of curbing it is here shown for making curbing inclined to the road, as in Fig. 18 and provided with flutes 12 (Fig. 4) having vertical light-reflecting faces 13 transverse to the length of the curb.

The form, as in Figs. 1 to 18 comprises a series of elongated sheet metal channel-shaped backing plates or members 15 (Fig. 1), which may be short as at 15a (Fig. 2) or several or many feet long as at 15b (Fig. 12). Said backing member 15 comprises an approximately upright plate or web 16 having a pitch to conform to the pitch of the active curb face and provided with outwardly laterally turned upper and lower flanges 17 and 18, the lower flange 18 being substantially perpendicular to the web, and the upper flange 17 being at such angle to the web as to render the upper flange substantially horizontal.

Secured upon the backing member 15, may be one or more of the die-cast form or mold plates 20, here shown nearly as wide as said web 16 and as long as the short channel member 15a, or secured end to end to each long channel member 15b and having perimetric flange portions 22, 23 engaged against the upper and lower margins of the long web of the long member 15b, or engaged against the perimeter of the short web of the short member 15a, at the inner face of the edge at the bottom of the web and near and spaced from and parallel to the top edge of the web, leaving a narrow face 24 (Fig. 3). Said flange portions 22, 23 are provided with bosses 25 (Figs. 1 to 3) at the inner faces thereof, for the reception of screws 26 passing through the web and engaged in said bosses to hold the form plates in place with the perimetric flange against the perimeter of said web face.

Said form plate, as shown, is provided on its working face, disposed away from the web, with feature-forming molding faces such as a plurality of vertical shoulders 28, 29, 30 perpendicular to the main plane of the plate, and faced all toward the same end 31 of the plate, for forming the molded reflector faces 13 (Fig. 12). Said shoulders may be evenly spaced along the plate and of a length slightly more than half the vertical width of the plate, terminating a short distance from the top of the plate and a greater distance from the bottom of the plate. The outer main edges 32 (Fig. 2) of the shoulders are substantially in a single plane parallel with the said web, and each edge 32 is connected to the inner main edge 33 of an adjacent shoulder by an inclined connecting face 34, 35 slightly convexed at the part 34 adjacent to the outer edge and convexed at the part 35 near the inner edge,

whereby the molding face of the plate is given a step formation.

The shoulders 28 nearest the plate ends are narrowest, with complementary connecting face portions 34', 35' extending from such narrowest shoulders 28 to the adjacent ends, the sum of the widths of said portions 33', 34' being substantially equal to the width of the connecting portions 34, 35, each said portion 34' or 35' forming, with an adjoining portion of the adjoining plate 15, a composite connecting face 34', 35' similar in shape and width to the first named connecting faces 34, 35.

The intermediate shoulders 29, 30 between said narrowest shoulders 28 are slightly wider relatively progressively wider as they are more remote from the end 31 to give a flutter effect to the reflected light as cars move along.

The distance between the molding face and said web is least at the bottom and top margins of the plate, the molding face at the top margin being formed with a wide rabbet 38, having a flat lower face 39 (Figs. 3 and 18) intersecting the shoulders, and an axially longitudinal cylindrical concaved face 40 extending from said flat face to the top face of the plate. The top face of the upper flange 17 (Fig. 18) serves as a guage for measuring the height of the curbing, and as a guide for a trowel or smoothing plate 42 guided by said top face and having a flat part 43 resting on said top face, a down-turned part 44 forming a guide shoulder engageable against the exposed part of the web 16, a downwardly offset part 45 engageable flat against the upper face of the form plate 20, and a curved part 46 complementing the curve of said concaved face 40 for completing the curve of the upper curved bevel 47 of the curbing, the edge 48 being made sufficiently sharp.

Said working face at the bottom margin has a wide flat base-forming portion 50 (Figs. 3 and 18) parallel to the web, and an inclined face 51 extending from said base portion 50 and intersecting obliquely across the lower part of said shoulders 28, 29, 30 and connecting faces 34, 35, to form a base 52 for the curb. Said curved molding and base 52 serve to hold automobile tires from contact with the sharp edges 32 (Fig. 2), thereby to prevent injury to the tires.

Said form plate 20 is hollowed out, as at 54 (Fig. 2), adjacent to the channel members in conformity to the shape of the molding face, whereby the form plate is rendered light in weight and of substantially constant thickness throughout.

Said backing members 15, 15a or 15b are placed in end-for-end relation, with adjacent ends of the said plates interengaged as in Fig. 8, and are thus secured by suitable means such as will now be described.

To this end interengaging key or clamping plates 56, 57 (Figs. 6 and 8) are secured flat on adjacent margins of the webs 16, one plate 56 being provided with a marginal recess 58 adjacent to the other plate, said other plate having a tongue 59 engaged in said recess to hold the form sections in alignment. Said tongue and the plate material adjacent to the recess have vertical flanges 60, 61 perpendicular to the plates for facilitating interengaging the plates. The margins of said key plates most remote from each other are upwardly converged in relation to each other and outwardly bent from the web to form converged wedge members 63. A yoke or binder plate 64 has inwardly turned down-

wardly diverged side flanges 65, adapted to engage around and under said wedge members 63 respectively, and to be forced downwardly on the wedge members with a wedging action to draw the form toward each other. The ends 22 (Fig. 2) of the form plate project very slightly beyond the backing plate, so that when the binder 64 is forced downwardly, said ends 32 will tightly engage. Said yoke plate has outwardly turned upper and lower flanges 66 to facilitate operating the yoke plate.

The long backing plates may be straight, for straight roads, as the backing plate 15b (Fig. 12), or they may be made curved in either direction, for curves, as the plates 15c (Figs. 15 and 17) and 15d (Fig. 16). When the plates are thus curved, the ends of the form plates may be left perpendicular as at 22 of Figs. 2, 12 and 17, or they may be slightly beveled in either direction, depending upon the direction of the curve, as at 22a of Fig. 15, or they may be respectively cylindrically convexed and concaved as at 22x and 22v of Figs. 13 and 16. The curved ends 22x and 22v are suitable for straight roadway or curves in either direction.

In molding the curbing at the side of the roadway, the form may be placed vertical, but is preferably placed at an angle, as in Fig. 18, in spaced relation with a suitable board or back plate 69, the upper parts of the board and the forms are held in spaced relation by suitable clamps and spacers until the concrete is poured and somewhat hardened.

The lower part of the forms may be supported in any suitable manner. Where there is an expansion joint at the side of the pavement, we may use a sheet metal supporting and retaining protection plate 70 having a lower vertical part 71 adapted to be disposed or secured against the outer face of the two-part metal strip 72 of the expansion joint 73 at the side of the pavement. To prevent concrete from entering the expansion space 75 the protection plate is bent to form a narrow plate-supporting shoulder part 76, and a wider downwardly offset flange 77, both upwardly inclined over the pavement, the latter having an upturned edge flange 78. The shoulder 76 or flange 77 or both may be riveted or otherwise secured to the form plate or backing plate or both, if desired; and the flange 77 may be rested on the edge of the pavement.

If desired, the curbing may be precast and then transported to the roadway and put in place. To this end we provide a form or mold as shown in Fig. 19 comprising a trough having sheet metal side walls 80, 81 and end walls 82, the bottom of the trough comprising an elongated sheet metal backing plate 83, 84, the part 83 thereof having a pitch relative to the top level of the trough corresponding to the pitch of the active curb face relative to the vertical back curb face, the part 84 being parallel to the vertical back face of the curb.

The ends of the side walls are provided with lateral flanges provided with perforated projections 86 secured thereon and passed through openings in the end walls and to form seats for wedges 87 for holding the walls together in a knockdown manner. Similar wedge connections 86, 87 hold in place angle irons 90, 91 on the inner bottom margin of the side walls to support the plate 83, 84 resting thereon. Other means may be used for securing the parts together.

One or more stamped or cast metal form or mold plates 20p are secured against said bottom

10 backing plate 83, 84 in any suitable manner or by screws as in Fig. 3. Said form plate or plates extend from end to end of the bottom backing plate, and are secured to the backing plate with the bottom edge face 51p spaced from, and parallel to, the adjacent side wall 80.

The form plate 20p is provided on its face disposed away from the bottom plate, with any desired molding faces or with faces providing transverse shoulders 28p similar to the shoulders 28 to 30 of Fig. 2, the outer main edge of each shoulder being connected by a connecting face to the inner main edge of an adjacent shoulder, whereby the working plate face of the plate is given a step formation as in Fig. 2.

The top margin of the molding face is formed with a wide deep groove 38p forming an axially longitudinally cylindrical concaved face intersecting at one side with said shoulders 28p, the other side merging tangentially into the adjacent side wall 81 for completing an upper curved bevel of the curbing. The working face 51p at the bottom margin of the form plate is spaced from the adjacent side wall 80 to leave exposed a wide flat base-forming portion 84 of the bottom plate substantially parallel to the top level of the trough. Said bottom margin 51p forms an inclined face extending from said base forming portion and intersecting obliquely across the lower part of said shoulders 28p and the connecting faces to form a base portion for the curbing.

35 The walls 80, 81, 82 are provided with top flanges 93 adapted to guide a straight-edge scraper, for scraping off excess concrete for making a smooth back face to the curbing.

Because of the releasable means of Figs. 6 to 8 for drawing toward each other and clamping adjacent ends of the backing plates to hold the plates in end-to-end series and to clamp said adjacent transverse ends of the form plates closely together, the new form is particularly suitable for the continuous molding of curbing in situ, as the cement or concrete may be poured against the molding faces in successive batches, each subsequent batch being poured before the adjacent batch is hardened but after a more remote batch has hardened sufficiently for the removal of the molding faces at the hardened batch. Then the releasable means at the hardened batch may be released, and the backing and form plates at the hardened batch may be removed and secured in place to the end of the series at the last poured batch, to allow a fresh batch to be poured upon the last poured batch while said last poured batch is sufficiently soft to integrally joint the fresh poured batch, whereby the continuous molding of curbing with a limited number of form plates is facilitated.

60 The invention claimed is:

1. A concrete mold including a rigid backing plate, a thin rigid face plate spaced from the backing plate and having end flanges extending toward and engaging with their free edges against the face of the backing plate at the ends thereof, and means for detachably securing the face plate on the backing plate.

65 2. A concrete mold including a rigid backing plate, a thin rigid face plate spaced from the backing plate and having end flanges extending toward and engaging with their free edges against the face of the backing plate at the ends thereof, means for detachably securing the face plate on the backing plate, and stiffening flanges extending rearward from the longitudinal edges of the backing plate.

3. A concrete mold including a rigid backing plate, a thin rigid face plate spaced from the backing plate and having end flanges extending toward and engaging with their free edges against the face of the backing plate at the ends thereof, means for detachably securing the face plate on the backing plate, and stiffening flanges extending rearward from the longitudinal edges of the backing plate and face plate.

4. Apparatus for molding concrete curbing comprising a face mold portion including a rigid plate having a flange at its upper edge extending at an acute angle away from the face of said portion, and a trowel member having a base portion forming an acute angled channel fitting on the angle at the junction of the plate and flange for guided sliding movement therealong.

5. Apparatus for molding concrete curbing comprising a plurality of units each consisting of a backing plate and a face plate secured thereto, each face plate having a pair of end flanges

extending to and resting on end portions of the backing plate, the flange at one end of each unit being convex in cross-section and the flange at the other end of each unit being concave in cross-section to fit the convex flange of an adjacent unit and permit close contact between the several face plates when the units are angularly disposed relative to each other.

6. Apparatus for molding a curb face at the side of a paved street wherein the street paving is spaced from the curb base by an expansion strip, said apparatus comprising a supporting plate having a vertical leg adapted to extend down into the space between the paving and base and having a trough-like portion adapted to extend over the paving at the upper edge of the vertical leg, and a face mold having a flanged portion at its lower edge fitting in said trough-like portion of the supporting plate.
